FRAME FOR A BELT SANDER

William Palmer Iggulden, Balcomb Park Lane,
Beaumaris, Victoria, Australia

Filed Feb. 3, 1964, Ser. No. 78,482

Claims priority, application Australia Aug. 16, 1962

Term of patent 14 years

(Cl. D37—1)

FIG. 1 is a rear perspective view taken from above, of a frame for a belt sander showing my new design; FIG. 2 is a front perspective view thereof, taken from below;

FIG. 3 is a top plan view thereof;
FIG. 4 is a right side elevational view thereof;
FIG. 5 is a left side elevational view thereof;
FIG. 6 is a rear elevational view thereof; and
FIG. 7 is a front elevational view thereof.

I claim:

The ornamental design for a frame for a belt sander, as shown.
